UNITED STATES PATENT OFFICE.

HARRY BURTON ALLYN, OF POUGHKEEPSIE, AND ANGELO TORQUATO BERTOLINI, OF NEW YORK, N. Y.

LIGHT ATTACHMENT FOR SEWING-MACHINES.

1,232,166.

Specification of Letters Patent.

Patented July 3, 1917.

Application filed December 7, 1916. Serial No. 135,557.

To all whom it may concern:

Be it known that we, HARRY B. ALLYN and ANGELO T. BERTOLINI, citizens of the United States, and residents, respectively, of 5 Poughkeepsie, in the county of Dutchess and State of New York, and the city of New York, borough of the Bronx, in the county of Bronx and State of New York, have invented a new and Improved Light Attachment for Sewing-Machines, of which the following is a full, clear, and exact description.

This invention relates to a lamp attachment for sewing machines, whereby the rays of light can be thrown in any desired direction for properly illuminating the work.

The general objects of the present invention are to improve the construction of light attachments for sewing machines so as to be reliable and efficient in use, comparatively simple and inexpensive to manufacture, and so designed as to provide for the universal adjustment of the lamp while the attachment is applied to the arm of the sewing machine.

A more specific object of the invention is 25 the provision of a novel bracket having attaching means especially designed to engage in an oil hole in the arm of the sewing machine, whereby the bracket can be firmly held in place while the lamp is adjustable to 30 various positions to produce the best illuminating effects.

Still another object of the invention is to provide a novel connection between the bracket and the lamp-carrying arm, where- 35 by the lamp is capable of adjustment to various positions.

With such objects in view, and others which will appear as the description proceeds, the invention comprises various novel 40 features of construction and arrangement of parts which will be set forth with particularity in the following description and claims appended hereto.

In the accompanying drawing, which 45 illustrates one embodiment of the invention and wherein similar characters of reference indicate corresponding parts in all the views.

Figure 1 is a front view of the light attachment applied to the arm of a sewing machine;

Fig. 2 is a plan view of the attachment;

Fig. 3 is a side view with the lamp thrown to an upstanding position;

Fig. 4 is a detail sectional view on the line 4—4, Fig. 2; and

Fig. 5 is a sectional view on the line 5—5, Fig. 2.

Referring to the drawing, 1 designates the attaching bracket of the device, 2 the tubular stem or arm adjustably mounted on the bracket, 3 an ordinary lamp socket, 4 an incandescent lamp, and 5 a shade which is rotatably mounted on the lamp socket so as to properly shade the eyes of the operator. The bracket 1 comprises an arm which has at one end a saddle 6 which engages over the arm A of a sewing machine, as shown by dotted lines in Fig. 1. This saddle or embracing portion 6 has a laterally extending lug 7 from which depends a stud 8. This stud 8 is adapted to enter a lubricating opening 9 in the arm of the sewing machine. The stud 8 has an internally threaded bore 10, and the lower end of the stud is split longitudinally to form jaws 11, and threaded in the stud is a longitudinally movable wedge 12 which spreads the jaws 11 so that they snugly fit in the opening 9 of the sewing machine arm, and thereby anchor the bracket 1 on the arm. The wedge has a slot 13 into which a screw-driver can enter in order to turn the wedge and thereby move it longitudinally. The bracket extends outwardly from the sewing machine arm in a horizontal position, and the outer end of the bracket has an upstanding ear 14. An L-shaped secondary bracket 15 is connected by a pivot 16 with the ear 14, and on this secondary bracket is mounted 90 the tubular arm 2.

As shown in Fig. 5, the tubular arm 2 passes through a clamping block 17 and through a clamping ring 18. The block 17 has a threaded opening 19 into which engages a screw 20 that passes upwardly through the horizontal member 21 of the secondary bracket 15. Washers of insulation 22 and 23 insulate the parts 17, 18 and 20 from the brackets and sewing machine arm. By turning the screw 20, the block 17 is drawn downwardly, and as the sleeve 18 is stationary, the tubular arm 2 will be clamped in the block and sleeve against longitudinal or rotary movement, but by loosening the screw 20, the tubular arm 2 can be adjusted to any desired position. To hold the screw 20 set, a jam nut 24 is threaded thereon and

jams on the washer 23. Through the tubular arm 2 passes a cord conductor 25 by which current is supplied to the incandescent lamp. By mounting the arm 2 in the manner specified it can be swung on a horizontal axis afforded by the pivot 16, or on a vertical axis afforded by the screw 20 and associated parts.

With a device constructed as set forth, the lamp can be positioned to the right or left of the needle α of the sewing machine, or in front or behind the same, whereby the rays of light will illuminate the work to the best advantage, and furthermore, the lamp can be thrown to an upstanding position for general illumination.

The wedge 12 is provided with a channel 26 through which the oil flows to an internal part of the machine.

From the foregoing description taken in connection with the accompanying drawings, the advantages of the construction and method of operation will be readily understood by those skilled in the art to which the invention appertains, and while we have described the principle of operation, together with the device which we now consider to be the best embodiment thereof, we desire to have it understood that the device shown is merely illustrative and that such changes may be made when desired as fall within the scope of the appended claims.

Having thus described our invention, we claim as new and desire to secure by Letters Patent:

1. A light attachment of the class described comprising a bracket having a saddle at one end, a depending stud on the saddle for engaging in an oil hole in the sewing machine arm, means for expanding the stud to fasten the bracket on the arm, and a lamp carried by the bracket. 40

2. A light attachment comprising a bracket formed with a member for embracing the arm of a sewing machine, a hollow stud on the said member for engaging in an oil hole in the arm, said stud being formed with jaws, a wedge in the stud for spreading the jaws, and a lamp carried by the bracket. 45

3. A light attachment comprising a bracket formed with a member for embracing the arm of a sewing machine, a hollow stud on the said member for engaging in an oil hole in the arm, said stud being formed with jaws, a wedge in the stud for spreading the jaws, and a lamp carried by the bracket, said wedge having an oil passage. 50

4. A device of the class described comprising a lamp-carrying bracket having a member at one end for embracing the arm of a sewing machine, a hollow internally threaded stud on the member for engaging in an oil hole of the machine arm, said stud being split longitudinally to form clamping jaws, and a wedge threaded in the stud to spread the jaws, and the wedge having a longitudinal oil passage. 55
